UNITED STATES PATENT OFFICE.

CHARLES A. JAYNES, OF ST. LOUIS, MISSOURI.

DESIGN FOR A WATER-CLOSET BOWL.

SPECIFICATION forming part of Design No. 20,659, dated April 7, 1891.

Application filed December 23, 1890. Serial No. 375,609. Term of patent 3½ years.

To all whom it may concern:

Be it known that I, CHARLES A. JAYNES, of St. Louis, Missouri, have invented and produced a new and original Design for Water-Closet Bowls, of which the following is a specification, reference being had to the accompanying photographs, forming part thereof, and in which—

Figure 1 is a view directly from the front of the newly-designed bowl. Fig. 2 is a top plan view of the bowl.

The leading feature of my design consists in the base of the bowl, which from the point of view of the photographs is arranged centrally beneath the bowl and presents a symmetrical appearance larger at its upper end and tapering downward in the lines of an ogee curve to its lower end.

The bowl A is round, with its wall a flat and

tapering downward. Its bottom a' is flat and 20 larger in diameter than the upper end of the base B, thus forming a pronounced offset in the outline of the structure at the junction of the bowl and base. The foot C at the lower end of the base is rounded and flat. 25

What I claim is—

The design for a water-closet bowl herein shown and described, the same comprising the circular bowl having the flat tapered wall, the centrally-arranged base tapering downward in the lines of an ogee curve, and the flat foot, as set forth. 30

Witness my hand this 16th day of December, 1890.

CHARLES A. JAYNES.
